UNITED STATES PATENT OFFICE

JOHN C. SUTTON, OF ROCKFORD, ILLINOIS, ASSIGNOR TO SUTTON SHOPS, INC., OF ROCKFORD, ILLINOIS, A CORPORATION OF ILLINOIS

CAP AND METHOD OF MAKING THE SAME

Application filed January 21, 1927, Serial No. 162,421. Renewed November 20, 1929.

This invention relates to caps of the kind commonly known as skeleton caps which are intended for general sporting and outdoor use, and has for its principal object the provision of a cap of improved construction and a novel method of making the same.

The cap provided in accordance with my invention is more attractive in appearance than any of this type heretofore made and is, furthermore, relatively inexpensive, the manufacturing cost having been reduced positively to a minimum as the result of the improved method which I have evolved for making the same.

The cap with which the present invention is concerned is characterized by a visor, headband, and spider top or crown of one or more strap members, built up of pieces of celluloid or other thin, normally resilient sheet material cut to shape and having their edge portions bound with a pliable binding material, the parts being attached to one another by sewing through the sheet material and binding material of the joining parts. The resulting article has a distinctly ornamental appearance as a result of the contrast of the transparent or colored celluloid with the opaque binding material.

My improved method of manufacturing this article greatly reduces labor cost and permits of increased production and consists in sewing bindings on the visor and on the strap members of the crown, and then, in one operation, fastening the visor to the headband in the sewing of the binding onto the lower edge portion of the headband, and fastening the strap members to the headband in the sewing of the binding onto the upper edge portion of the headband. A further feature in regard to the fastening of the strap members of the crown is to provide a fold of the binding material on the band wherein the raw or unfinished ends of the strap members are fastened to the band by sewing through the binding material and sheet material of the two parts. As a result of this construction the raw ends are concealed and the cap presents a more finished and workmanlike appear-

ance. In a similar manner a sweat band is fastened to the headband by inserting the edge thereof within the fold of the binding material on the lower edge portion of the headband, the sweat band being thereby united with the headband and visor in the same operation when the binding material is sewed onto the headband.

The invention is illustrated in the accompanying drawings wherein—

Figure 1 is a perspective view of a skeleton cap made in accordance with my invention;

Fig. 2 is a central longitudinal section therethrough;

Fig. 3 is a more or less diagrammatic view showing in plan the arrangement of the visor, band and crown strap members during the operation of joining the parts together according to my improved method;

Fig. 4 is an enlarged sectional detail taken on the line 4—4 of Fig. 3 illustrating the finished connection between the band and one of the strap members of the crown; and

Fig. 5 is an enlarged section detail taken on the line 5—5 of Fig. 3 showing how the two pieces of binding material are folded over the edges of the headband to permit the insertion of the sweat band at one edge of the headband and the insertion of the ends of the strap members at the other edge, and showing further how the visor is guided for proper attachment to the band.

The same reference numerals are applied to corresponding parts throughout the views.

Referring first to Figs. 1 and 2 for an understanding of the kind of cap with which the present invention is concerned and also for a description of certain improvements in structural details provided in accordance with the present invention, it will be seen that the skeleton cap comprises a visor generally designated by the reference numeral 5, a headband 6, and one or more strap members 7 constituting a skeleton top or crown. The headband in the present case is provided with an elastic insert 8, preferably in the back, to accommodate the band to the

wearer's head so as to avoid the necessity for providing many close sizes of caps. As distinguished from the ordinary skeleton cap of fabric construction, which were objectionable because of their limpness and the awkwardness in the handling thereof and their tendency to get out of shape, the cap of the present invention is one of lighter and cooler construction, is at least equally durable and keeps its proper shape, besides being far more attractive in its appearance, and being easier to handle in putting on and taking off. These characteristics referred to are secured by providing the visor, headband and crown strap members of a thin, normally resilient sheet material, such as celluloid or any other plastic composition material having similar properties, cut to shape and bound about their marginal edges with a pliable binding material, such as a light imitation leather or leatherette or any woven or fabricated material, the parts referred to being united by sewing through the binding material and sheet material of the joining parts. The binding material affords the desired durability in the joints and makes for firm and permanent connections, whereas the celluloid itself would crack and tear and be otherwise unsuited to such connection. Thus, the visor 5 comprises a body part 10 of sheet celluloid bound about the outer edge by a binding 11 turned over the marginal edge and sewed as indicated at 12 in Fig. 2. The inner edge is likewise bound, as indicated at 13, the binding being turned over and sewed to the marginal edge of the visor, as indicated at 14. The headband 6 comprises a body part 15 of sheet celluloid with bindings 16 and 17 sewed to the lower and upper edges thereof, as indicated at 18 and 19, respectively. The crown strap members 7 each comprise a body part 20 of celluloid with bindings 21 sewed to the marginal edges thereof. The stitching at 18 serves to join the visor to the headband, while the stitching at 19 serves to join the ends of the crown strap members to the headband, the connection in each case being a durable and permanent one by reason of the fact that the stitching passes through the sheet material and binding material of both of the joining parts. The details thus far described are generally illustrated and described in my patent, No. 1,599,978, issued September 14, 1926, and generally stated, in themselves, form no special part of the present invention. The strap members of the crown are all joined together by a single button rivet, as indicated at 22. According to the present invention, a sweat band 23 has the marginal edge thereof inserted in the fold of the binding 16 between the inner ply thereof and the body part 15 of the headband, as most clearly appears in Fig. 2. By reason of this arrangement it is possible to attach the sweat band with the visor to the headband in one operation when the binding 16 is sewed onto the headband, as indicated at 18. In a similar manner I prefer to have the raw and unfinished ends of the strap member 7 of the crown inserted in a fold 24 of the binding 17 on the upper edge portion of the headband 6 (see Fig. 4) so as to be attached to the headband when the binding 17 is sewed thereon, as indicated at 19. The binding 17 is folded two ways, as indicated, to form an approximately S-shaped cross-section, in one fold of which the marginal edge of the headband is received and in the other fold of which the end of the strap member is received. Thus, the raw or unfinished ends of the strap members are concealed and a much more workmanlike and neat appearing cap is produced, the connection being at the same time much stronger and more durable by reason of the additional fold of binding material.

The cap above described is obviously of relatively economical construction but by virtue of the improved method of making the same, which will now be described, the cap is rendered available at an exceptionally low cost considering the good grade and quality thereof. According to this method, which I have illustrated more or less diagrammatically in Figs. 3 and 5, the visor 5 is made up separately with the bindings 11 and 13 sewed thereon, as indicated at 12 and 14, respectively. The crown or spider top is also produced from a plurality of strap members joined together by the rivet 22. Then the visor and the crown strap members are both joined in one operation to the lower and upper edges, respectively, of the band 6 in the sewing of the bindings 16 and 17 to the lower and upper edges of the latter. Furthermore, the sweat band 23 is assembled on the headband with the visor by the same stitches. This obviously eliminates a number of separate time-consuming and expensive operations and the production time per cap is reduced practically to a minimum. As a matter of fact, the present method permits production at the rate of two or three times as many caps per operator as could be produced where the caps were assembled part by part. A two-needle machine operating along the two edges of the band is employed, these needles being indicated at 25 and 26, and serving to perform the stitching indicated at 18 and 19. A guide, designated generally by the reference numeral 27, is disposed in front of the needles on a plate 28 fixed in any suitable manner on the table of the machine. The guide 27 comprises two sheet metal parts 29 and 30 soldered, welded, or otherwise suitably secured, in laterally spaced relation on the plate 28. The part 29 is generally V-shaped in cross-section so as to receive one edge of

the strip 15 in the crotch 31 thereof. The other edge of the strip is received in the lower turn 32 of the guide part 30. The part 29 has the edge portions of the two arms thereof bent inwardly, as indicated at 5 33, whereby to receive the folded strip of binding material 16. The guide part 30 on the other hand is suitably bent to receive the strip of binding material 17 folded two ways to an approximately S-shaped cross-section, 10 as will readily appear in Fig. 5. The one edge of the celluloid strip 15 is thus guided for reception in the fold of the binding 16 and, as most clearly appears in Fig. 5, the 15 edge of the sweat band 23 is likewise inserted in the fold of the binding material. The other edge of the strip 15 is received in one fold of the binding 17, the other fold being arranged to receive the end of the strap 20 member, as indicated by the dotted lines in Fig. 5. In practice the operator starts sewing the two bindings onto the edges of the headband strip 15 and enters the end of one of the strap members 7 within the fold 24 25 so as to attach the strap member to the headband by the stitching 19 which, of course, serves primarily to fasten the binding 17 to the headband. When the second strap end is about to be fastened in this manner the 30 one end of the visor is brought into position, as shown in Fig. 3, and a few stitches suffice to attach the end thereof to the headband, the stitching going through the bindings and sheet material of both the visor and headband in a similar manner as in the connection 35 of the strap end therewith. A guide block 34 is provided on the under side of the plate 28 to bear against the inner edge of the visor and guide the same as it is fed toward the needle 25 as the sewing proceeds. In 40 actual practice, it is only necessary to commence the sewing of the visor onto the band and after that the visor is guided into position without any further attention, the operator being concerned only with the matter of inserting the strap ends at regular 45 intervals into the fold of the binding 17 so as to have all of the parts assembled together in their proper relationship. An operator soon becomes expert in the handling of the 50 cap parts and when provided with a machine capable of stitching at a high speed will produce as many as 800 caps in an average day of eight hours. These figures are given merely to indicate the possibilities for 55 volume production when the method as herein outlined is followed. When the elastic 8, or any other means, is provided to complete the headband the cap is ready for use. It 60 has been found that far greater uniformity in the characteristics of the product is only one of the desirable results obtained in the practice of my improved method. Caps produced by other methods have been found to 65 lack as neat, trim and workmanlike an ap-

pearance, especially in the joining of the visor to the headband, the fastening of the two parts in any other way having been found to result in the celluloid of the band or visor being kinked or otherwise distorted. 70

It is believed the foregoing description conveys a sufficiently clear understanding of my invention that anyone skilled in the art to which the same relates will readily appreciate all of its advantageous features and 75 will be easily enabled to practice the same. 75

I claim:

1. A skeleton cap comprising a visor, a headband, and a crown, at least the first two named parts comprising pieces of thin, so 80 normally resilient sheet material having their edge portions bound with a pliable binding material folded over the marginal edges thereof, a sweat band for the head band having its edge received with the edge 85 of the head band in the fold of the binding for said head band, the visor being attached to the lower edge portion of the band by fastening means passing through the sheet material and binding material of the 90 visor and band as well as through the sweat band, and means for holding the crown in assembled relation with the visor and headband. 95

2. The method of making a cap comprising a visor, a headband, and a crown strap wherein the visor, headband and strap members comprise pieces of normally resilient sheet material cut to shape and provided with binding material on the marginal edge 100 portions thereof whereby the parts named may be united by fastening means passing through the sheet material and binding material of the joining parts, the said method consisting in sewing binding material on the marginal edges of the sheet material of the visor, and likewise sewing binding material on the marginal edges of the sheet material of the strap member, and finally folding two pieces of binding material over the 105 two marginal edges of the sheet material of the band and sewing the same thereto, while at the same time sewing the visor to one edge of the band by sewing through the binding material and sheet material of both 110 the visor and band, and similarly uniting the strap member with the other edge of the band by sewing through the binding material and sheet material of both the strap member and band. 115

3. The method as set forth in claim 2 which consists further in inserting the edge of a sweat band within the fold of the binding on the lower edge portion of the head band whereby both the sweat band and visor are united with the headband in the same sewing operation by stitching through the sweat band and through the sheet material and binding material of the visor and headband. 120

4. The method of making a cap comprising a visor, a head band, and a crown strap wherein the visor, head band and strap members comprise pieces of normally resilient sheet material cut to shape and provided with binding material on the marginal edge portions thereof whereby the parts named may be united by fastening means passing through the sheet material and binding material of the joining parts, the said method consisting first in sewing binding material on the marginal edges of the sheet material of said visor, then folding binding material over the marginal edge of the sheet material of the band and, with it, over the marginal edge of a sweat band and sewing the binding material thereto while at the same time sewing the visor to the band by sewing through the binding material and sheet material of the visor and band as well as through the sweat band, and sewing the ends of the strap member to the band.

5. The method of making a cap comprising a visor, a head band, and a crown strap wherein the visor, head band and strap members comprise pieces of normally resilient sheet material cut to shape and provided with binding material on the marginal edge portions thereof whereby the parts named may be united by fastening means passing through the sheet material and binding material of the joining parts, the said method consisting in sewing binding material on the marginal edges of the sheet material of the visor, and likewise sewing binding material on the marginal edges of the sheet material of the strap member, and, in a final step, folding a piece of binding material over one of the marginal edges of the sheet material of the band and sewing the same thereto while at the same time sewing the visor to the band by sewing through the binding material and sheet material of the visor and band, and simultaneously folding another piece of binding material two ways to approximate an **S** cross-section, inserting the other edge of the sheet material of the band in one fold of said binding and sewing the same thereto and inserting, at spaced points, the ends of the strap member in the other fold of said binding and sewing the same to the band with the binding material, thus uniting the strap member with the band by sewing through the binding material and sheet material of the strap member and band.

In witness of the foregoing I affix my signature.

JOHN C. SUTTON.
